(57) **CLAIM**

The ornamental design for a ventilation fan housing and duct connector assembly, as shown and described.

DESCRIPTION

FIG. 1 is a top, left, front axonometric view of a ventilation fan housing and duct connector assembly showing my new design.

FIG. 2 is a front view thereof.

FIG. 3 is a rear view thereof.

FIG. 4 is a right side view thereof.

FIG. 5 is a left side view thereof.

FIG. 6 is a top plan view thereof; and,

FIG. 7 is a bottom plan view thereof.

The broken lines in the figures represent features of the article of manufacture that form no part of the claimed design.

1 Claim, 7 Drawing Sheets
